IMPROVEMENT IN LANTERNS.

RICHARD CHESTER, OF CHICAGO, ILLINOIS.

Letters Patent No. 60,140, dated December 4, 1866.

SPECIFICATION.

TO ALL WHOM IT MAY CONCERN:

Be it known that I, RICHARD CHESTER, of Chicago, in the county of Cook, and State of Illinois, have invented a new and useful Improvement in Lanterns; and I do hereby declare that the following is a full, clear, and exact description of the same, reference being had to the accompanying drawings, and the letters and figures marked thereon, which form part of this specification.

The nature of my invention consists in a novel arrangement for admitting air into the lantern, without danger of extinguishing the flame, in case of the wind blowing into the apertures; and also a novel arrangement in the top of the lantern, whereby the heated air readily passes out, while the wind cannot blow out the flame. To enable those skilled in the art to understand how to construct and use my invention, I will proceed to describe the same with particularity, making reference, in so doing, to the aforesaid drawings, in which—

Figure 1 represents a side elevation of my invention, the door of the lantern being open.

Figure 2 is a vertical central section of the same; and

Figure 3 is a plan view of the horizontal plate G.

The same letters of reference in the different figures denote the same parts of my invention.

A represents the enclosure of the lantern, which consists of a rectangular frame, containing four panes of glass of the proper configuration, the same being narrower at the top, as shown. One of said sides, marked A', is hinged so as to form a door, as shown, being secured firmly when shut, by means of a pin or rod marked a, passing through the sockets, b' b, upon the frame, and the tubular catch, a', upon the door. This enclosure, A, is securely guarded against breakage or injury, by means of the wire-guards, B, arranged as shown. C represents a platform or rest, arranged a suitable distance above the bottom of the lantern, E, provided with guides, c c, upon each side, upon and within which the oil cup, D, may slide and be withdrawn at pleasure, by means of the ring, d, or its equivalent for that purpose. Through the centre of the bottom, E, there are suitable apertures for admitting air into the lantern, above which perforations is arranged the perforated enclosure, marked F, which serves to disperse the wind and break its force before entering the enclosure of the lantern, which entrance is effected in the direction of the arrows, as shown, the platform deflecting the currents of air away from the flame until the force of the wind is expended, thus preventing the extinguishing of the flame thereby. In the top of the lantern is arranged the plate, G, closing the lower part of the enclosure of the lantern from the top, except at the four corners, as shown in fig. 3, through which openings the heated air rises and passes out through the tubes H. The tubes H are closed at their outer ends by perforated caps, to break the force of the wind, while their inner ends extend within the top of the lantern far enough to give the wind the proper direction to pass out through the opposite tube, and not deflect down upon the flame, which is further prevented by the arrangement of the said horizontal plate, G.

Having described the nature, construction, and operation of my invention, I will now specify what I claim and desire to secure by Letters Patent:

1. I claim the arrangement of the perforations in the centre of the bottom E, and the perforated enclosure F, arranged beneath the platform C, for the lamp, as and for the purposes described.

2. I claim the horizontal tubes H, provided with perforated cups, and extending within the lantern top, as shown, in combination with the diaphragm G, having openings at the corners, out of the range of said tubes, as herein specified and set forth.

RICH. CHESTER.
